United States Patent

Des. 240,703
Patented July 27, 1976

240,703

DRILL HOLDER

William D. Russell, San Diego, Calif., assignor to
Portalig Tool Company, San Diego, Calif.

Filed Feb. 7, 1975, Ser. No. 548,154

Term of patent 14 years

Int. Cl. D8—05

U.S. Cl. D8—71

FIG. 1 is a perspective view of a drill holder with a drill shown in phantom lines for illustrative purposes only;

FIG. 2 is a front elevational view;

FIG. 3 is a right side view taken along line 3—3 of FIG. 2;

FIG. 4 is a rear elevational view taken along the line 4—4 of FIG. 3, and

FIG. 5 is a left side view taken along line 5—5 of FIG. 2.

I claim:

The ornamental design for a drill holder, substantially as shown and described.
